WASHING MACHINE SUPPLY AND DRAIN UNIT

Charles W. Dick, Paducah, Ky., and Guy L. Gray, Rte. 1,
Paducah, Ky.; said Dick assignor to said Gray

Filed Dec. 15, 1958, Ser. No. 53,777

Term of patent 14 years

(Cl. D91—3)

FIG. 1

FIG. 2

FIG. 3

FIG. 1 is a perspective view of a washing machine supply and drain unit embodying our new design.

FIG. 2 is a top plan view; and

FIG. 3 is an end elevation looking at the left end of FIG. 1.

We claim:

The ornamental design for a washing machine supply and drain unit, as shown.
